CIRCUIT BREAKER

Raymond N. Rowe, Plainville, Conn., assignor to
 The Trumbull Electric Manufacturing Company,
 Plainville, Conn., a corporation of Connecticut

Application September 28, 1935, Serial No. 42,595

1 Claim. (Cl. 200—147)

This invention relates to a heavy duty switch or circuit breaker and has for one object to increase the efficiency of such constructions.

Another object is to provide an enclosed arc chamber for a conventional type of quick break or snap action switch or circuit breaker.

Another object is to provide a novel type magnetic blow-out device for extinguishing an arc that may be formed on opening the switch.

10 The invention contemplates the employment of a moving magnetic field for dispersing the arc which tends to form.

Referring to the drawing

Fig. 1 is a side elevation of one embodiment of this invention with parts broken away.

Fig. 2 is a section of a portion of this device on the line 2—2 of Fig. 1.

Fig. 3 is a section on the line 3—3 of Fig. 2. The snap action may be of any suitable type.

20 Fig. 4 is a view of a split washer.

One electrode or switch contact member in this invention is the shaft 10 preferably of non-magnetic material which is conductive, such as copper or brass.

25 The movable switch contact member 11 is slideable radially of the shaft 10 and its contact member 10' for engagement and disengagement with the surface of the contact 10'. On opening the switch by movement of the contact member 11 away from the contact 10', an arc may occur in the space 12 between the electrodes and under this invention a new type of magnetic blow-out is provided for any such arc.

30 The current passing through this switch is connected at the terminal 13 and thence passes through the U shaped thermostatic member 14, shown in dotted lines because such is not a part of this invention, the current passing up one leg and down the other of the U shaped thermo-static element, from whence it passes through the flexible connection or pigtail 15 secured to one end of the movable switch member 11. The switch member 11 is adapted to slide within a guide bearing 16 formed in the metal housing 17 surrounding the space in which any arc may occur.

35 A conductor 17 is spirally wound around one end of the shaft 10 and a similar conductor 18 wound around the other end of the same shaft 10, these coils being connected to the same shaft member 10 or in parallel, their opposite ends being connected to the other terminal 19 of the switch. The coils being in parallel and wound in the same direction assist one another in directing the electromagnetic field between the

coils so that the flux is substantially parallel to the cylindrical surface 10.

The metal housing 20, around the contact 10' and the arcing space 12, is likewise of non-magnetic material as is the switch part 11. Holes 21 are drilled and tapped in this ring for the purpose of receiving screws 22 which hold the coils and their housings in position. Contiguous the sides of the ring 20 are washers 23 of insulating material which is adapted to withstand the high temperature from close proximity of an arc, such insulating washers being of mica or some phenolic condensation product or asbestos or other suitable material.

40 In order to distribute the flux density substantially uniformly radially and circumferentially around the contact 10', split washers 24 and 25 of magnetic material are located between the coils 17 and 18 and the insulating washers 23. On the opposite side of the coils 17 and 18 are arranged insulating washers 26 and 27 to safeguard the insulation of each of the coils 17 and 18.

45 Surrounding each of these coils is a housing 28 and 29 of molded or other insulating material clamped in place by screws 22 as shown in Figs. 2 and 3.

The actuating mechanism for the movable switch part 11 includes a handle member 30 pivoted as indicated for moving the spring 31 each side of its pivot in producing a quick make and break toggle movement for the switch member 11. On closing the switch 11 by moving the handle 30 to the right, the switch member contacts with the stationary contact member 10'. Should the thermostatic element 14 be bent to the left in Fig. 1 and release the lever 32, the springs 33 being heavier than the springs 31 will cause the switch member 11 to be snapped open without the handle 30 moving. Manual movement of the handle 30 to the open circuit position indicated may then press down the lever 32 and reset it under the thermostatic latch.

50 The coils 17 and 18 are of insulated wire wound so that opposite poles are on opposite sides of the arc space, in other words, so that the split steel washers 24 and 25 are of opposite polarity.

55 It has been found that the efficiency of this construction has been increased by providing the shaft 10 with a silver alloy contact portion 10' and by either providing the movable contact member 11 with a similar contact portion or by making the entire body of contact member 11 of a suitable alloy which is preferably of the silver type.

A noteworthy feature of this invention is believed to be the substantially uniform distribution of the flux both circumferentially and radially around the shaft member 10. When both coils assist in directing the flux straight across between the split washers of magnetic material, there is a tendency for the arc to be moved around the circumference of the cylindrical electrode until it has lengthened sufficiently to break.

10 While the flux exerts an effort to move substantially the entire arc, it will be understood that at least the end of the arc adjacent the cylindrical electrode is adapted to be rotated far enough until broken. The flux rotates the arc 15 so rapidly as to prevent it from localizing and ionizing at any point and tests have shown this switch, of a size only slightly larger than that shown in the drawing, to be capable of breaking approximately 5000 amperes at 440 volts with this 20 single pole arrangement illustrated.

I claim:

An electrical switch including a central sub-

stantially cylindrical core of non-magnetic and conductive material, two blow-out coils located on either end of said core, washers of magnetic material upon said core and adjacent said coils whereby the space between said coils carries substantially uniform magnetic flux, said core constituting one electrode, another electrode contacting with the periphery of said cylindrical core and means for moving said last mentioned electrode radially away from said core, said coils being in electrical circuit with said electrodes, whereby the uniform magnetic field and the cylindrical configuration of said non-magnetic core cause the arc produced upon separating said electrodes to assume a substantially uniform spiral configuration about said core, and substantially air-tight housing means enclosing said space between said coils, whereby said arc will be more readily extinguished.

RAYMOND N. ROWE.
